United States Patent Office

Des. 210,936
Patented May 7, 1968

210,936

ORNAMENTAL RAILING

Louis Blum and William J. Horgan, Jr., Pittsburgh, Pa.,
assignors to Blumcraft of Pittsburgh, Pittsburgh, Pa.

Filed Mar. 31, 1967, Ser. No. 6,462

Term of patent 14 years

(Cl. D13—7)

Fig. 1

Fig. 3

Fig. 2

FIG. 1 is a perspective view looking from one side at a railing embodying our new design;

FIG. 2 is a perspective view looking from the other side at the railing of FIG. 1;

FIG. 3 is a section taken along line III—III of FIG. 1.
We claim:

The ornamental design for an ornamental railing, as shown.
